UNITED STATES PATENT OFFICE.

TRUMAN W. POST, OF PROVIDENCE, RHODE ISLAND, ASSIGNOR TO ELECTRIC AUTOLITE CORPORATION, OF TOLEDO, OHIO, A CORPORATION OF DELAWARE.

HEADLIGHT.

Application filed September 12, 1917. Serial No. 190,977.

To all whom it may concern:

Be it known that I, TRUMAN W. Post, a citizen of the United States, residing at Providence, in the county of Providence and State of Rhode Island, have invented certain new and useful Improvements in Headlights, of which I declare the following to be a full, clear, and exact description.

This invention relates to improvements in headlights and more particularly to automobile headlights of the tilting reflector type.

In an automobile headlight of the tilting reflector type, in which means are provided for tilting the reflector from a position in which it gives a substantially horizontal beam of light to one in which the beam of light is deflected downwardly on the ground, it is highly desirable that the angle at which the beam of light is deflected downwardly be quite accurately determined. If the deflection is not great enough the beam of light will glare, while if it is too great the ground in front of the moving vehicle will not be illuminated to so great a distance as would be possible without the headlights glaring.

It is also highly desirable to provide means whereby the deflected position of each headlight can be independently adjusted without disturbing the other or a common operating means, because if the beams of light are deflected downwardly at different angles they will strike the ground at different points, giving an effect which is very annoying to the driver.

It is also highly desirable, and in fact, essential to provide entirely automatic means which will insure that the headlight will come to rest in but two positions, namely: The horizontal position and the completely deflected position.

It may also be deemed desirable to provide means whereby the total angular movement of the reflector will be fixed, but the limits of said movement may be adjusted at will.

It is therefore an object of my invention to provide in a mechanically operated headlight, mechanism having these advantages and to provide tilting mechanism which, in its normal use, always moves the reflector to its extreme position in either direction.

Another object is to provide for means for effecting individual adjustment of each re-

flector of a pair for both the initial and the tilted position while providing also means for the simultaneous movement of the two headlights by the operation of a single actuating member.

Further objects of this invention relate to economies of manufacture and details of construction as will hereinafter appear from the detailed description to follow. I accomplish the objects of my invention in one instance by the devices and means described in the following specification, but it is evident that the same may be varied widely without departing from the scope of the invention as pointed out in the appended claims. A structure constituting one embodiment of my invention, which may be the preferred, is illustrated in the accompanying drawings forming a part hereof in which:

Figure I is a view, in side elevation, of the forward part of a motor vehicle equipped with headlights embodying my invention.

Figure II is a vertical, sectional view taken through one of the headlights.

Figure III is a detail, fragmentary, sectional view taken substantially on the line III—III of Figure II.

Figure IV is a transverse, sectional view taken substantially on the line IV—IV of Figure II.

Figure V is a fragmentary view, in side elevation, showing the operating lever and the casing therefor secured to the steering column.

Figure VI is a plan view of the operating lever casing with the cover removed, taken substantially on the line VI—VI of Figure V.

Figure VII is a detail, sectional view taken substantially on the line VII—VII of Figure VI.

Figure VIII is a detail, perspective view of the operating lever, and Fig. IX is a diagrammatic view showing connections to two head lights.

In the drawings, similar reference numerals refer to similar parts throughout the several views and the sectional views are taken looking in the direction of the arrows at the ends of the section lines.

Considering the numbered parts of the drawing, I have shown a motor vehicle carrying at the forward ends of the frame

the supporting standards 11 in which the headlight casings 12 are mounted in the usual manner. The forward end of the casing 12 is closed by the lens 13 carried by 5 a ring 14 which is secured to the casing in the usual manner. A parabolic reflector 15 is pivotally mounted in the casing 12 on pivots (not shown) located approximately in the plane of the glass 20 so that 10 the reflector may turn on a horizontal axis and said reflector carries a socket 16 at the rear end thereof in which the light bulb 17 is mounted. An annular, forwardly facing groove 19 is formed at the forward end 15 of the reflector and a packing ring 18 of wicking or other suitable material is disposed in said groove. A pane of glass 20 is placed over the forward end of the reflector with its periphery abutting said 20 packing ring, and held in place by the split clamping ring 21, the ends of which are provided with radially extending ears 22, through which the bolt 23 passes to draw the parts of the clamping ring together and 25 hold it in place. A connector 24 is carried by the rear end of the casing 12 and electrically connected with the sockets 16 by the wires 25.

A clamp 26 embraces the socket 16 between the reflector 15 and the casing 12, said clamp being provided with ears 28 through which the bolt 27 passes. The wire 29 is secured at its upper end to the bolt 27 and an upper disc 30 and a lower disc 35 31 are mounted on said wire, as shown in Figure III. A compression spring 32 is disposed around said wire 28 with its ends abutting said discs. The boss 33 is secured to the casing 12 in any suitable manner and 40 carries a sleeve 34, the inner end of which extends into the casing 12 and the lower end of which is split at 35. A clamp 36 is provided with laterally extending ears through which the bolt 37 passes, to draw 45 the split ends of the sleeve 34 together. An inner sleeve 38 is slidably mounted in the sleeve 34 and carries a pin 39 which extends through a loop 40, formed in the wire 29, the adjacent portions of the wire forming 50 the loop being soldered or otherwise secured together at 41 so that the length of said loop is fixed. The lower end of said sleeve 38 is split at 39' as shown in Figures III and IV. A hook 42 is formed on the lower end of 55 the wire 29 adjacent the lower end of the sleeve 38 and is adapted to be engaged by an eye 45 formed on the end of the wire 44 which is disposed in the tubing 43, the upper end of which is mounted in the lower 60 end of the sleeve 38. This tubing 43 may very well be formed from hollow, flexible shafting.

The tubing 43 extends from each headlight to the steering column 68 and up the 65 steering column to a position within easy

reaching distance of the steering wheel where a casing 46 is secured to the steering column by the clips 47, the ends of which extend through the lugs 48 projecting from the sides of the casing 46 and are secured thereto by the nuts 49. A cover 50 is provided for the casing 46, being secured thereto by the screws 51. Grooves 52 are provided in the lower end of the casing and the ends of the tubes 43 lie in said grooves. The cover 50 is likewise provided with grooves 53 co-operating with the grooves 52 so that when the cover 50 is secured in place on the casing 46, the ends of the tubes 43 are clamped in said grooves. An operating lever 54 is fulcrumed at 55 in the casing 46 with its operating end extending through an opening 56 in the side of the casing. A supplementary latching lever 57 is fulcrumed at 58 on the lever 54, said lever 54 being U-shaped so the supplementary latching lever 57 is disposed within the channel of the lever 54. A spring 60 is secured to the lever 57, the end of the spring 60 being turned laterally and extending into the lever 57 at 61 and said lever has a beveled nose 59 which is adapted to engage a post 62 in the casing 46. An equalizing block 63 is disposed in the casing 46 and the ends of the wires 44 are secured to said block by means of the screws 64. The block 63 is connected to the lever 54 by the spring 65, which is connected to the block 63 at 66 and to the pin 67 screwed into the lever 54. The spring 65 is much stiffer than the spring 32 so that the spring 32 will operate in preference to the spring 65.

From the description of the parts given above, the operation of this device should be very readily understood. The parts are shown in full lines in the position which they occupy, in order to throw a horizontal beam of light. By a reference to Figure VI, it will be seen that the lever 54 is held in its upper position by the engagement of the nose 59 with the post 62. When the driver wishes to throw the reflectors into non-glaring position, he presses down on the latching lever 57 which releases the nose 59 from engagement with the post 62 and permits the lever 54 to swing downwardly to the position shown in dotted lines. This movement is effected by the spring 32 which presses upwardly on the disc 30, which abuts the clamp 26 and throws the reflector to the position shown in dotted lines. This movement is limited by the engagement of the loop 40 in the wire 29 with the pin 39 which is fixed in the sleeve 38. It will be seen that this pin limits the movement of the wire 29 in both directions. The total angular movement of the reflector is fixed, being determined by the length of the loop 40. The limits of said angular movement, however, may be varied by adjusting the sleeve 38

which carries the pin 39. This adjustment is effected by loosening the clamp 36 and moving the sleeve 38 within the sleeve 34 which is fixed to the casing. It will be seen

- 5 that this adjustment may be effected without disturbing the operating mechanism at all. The reflector is held in its horizontal position by means of the supplementary latching lever 57, and when this is released and the 10 lever 54 is moved so that the reflector is in any position other than the horizontal position, the spring 32 will automatically move the reflector as far as permitted by the engagement of the loop 40 with the pin 39, so 15 that the reflector cannot remain in any position intermediate to its limits of movement.

It will be seen that the lever 54 is so arranged in the casing that it will be up when 20 the beam of light is up and that it will be down when the beam of light is deflected, so that it indicates to the driver whether the beam of light is in the horizontal position or not. The spring 65 forms a slightly resilient 25 connection between the wires 44 and the lever 54 so that even if the stop 39 does not exactly correspond to the position of the post 62 the lever can be latched in its upper position. By means of the hook and eye 30 connection between the wire 29 and the wire 44, the headlight and its tilting mechanism may be removed without disturbing the tube 43 and the wire 44 carried thereby. The 35 only adjustment which is possible is that of the sleeve 38 and this adjustment cannot alter the throw of the reflector but merely changes the limits of the throw. By means of this adjustment, the deflected position of the reflectors can be varied until they strike 40 the ground in front of the vehicle at the same angle and at a proper angle so as to prevent the glaring of the headlights.

I am aware that the particular embodiment of my invention, here shown and described, is susceptible of considerable variation without departing from the spirit thereof and, therefore, I desire to claim my invention broadly, as indicated by the appended claims.

50 Having thus described my invention, what I claim as new and desire to secure by Letters Patent, is:

1. In a device of the class described, the 55 combination of a plurality of headlight casings, a tiltable reflector in each of said casings, adjustable stop means for rendering the limits of movement of each reflector independent of the other, and means for tilting both of said reflectors, said means co including a common controlling member and connections with said reflectors providing relative self-adjustment.

2. In a device of the class described, the 60 combination of a casing having a lens, a tiltable reflector, adjustable means for lim-

iting the movement of said reflector, and means for moving said reflector including an element adapted to yield when said reflector has reached said limiting means.

3. In a device of the class described, the 70 combination of a casing having a lens, a tiltable reflector mounted in said casing, adjustable means to limit the tilting of said reflector, means to tilt said reflector, and a spring interposed in said tilting means 75 adapted to yield when said reflector is stopped by said limiting means.

4. In a device of the class described, the combination of a casing, a reflector movably mounted therein, means including a 80 yieldable member for moving said reflector in one direction, resilient means for moving said reflector in the opposite direction and stop means for determining the limiting positions of said reflector whereby the 85 same is yieldingly held against a stop in one or the other of its limiting positions.

5. In a device of the class described, the combination of a plurality of head-light casings, the reflector mounted to tilt in 90 each of said casings, means including a common controlling element for moving each of said reflectors to a limited non-glare position and a single adjusting means for each head-light for independently determining both the initial and the terminal positions of the respective reflectors. 95

6. A device of the class described, comprising the combination of a casing; a reflector pivotally mounted therein; means 100 for moving said reflector; and a single stop for limiting the movement of said reflector in both directions.

7. A device of the class described, comprising the combination of a casing; a reflector pivotally mounted therein; means 105 for moving said reflector including a movable member; and a single stop to limit the movement of said member in both directions to limit the angular movement of 110 said reflector.

8. A device of the class described, comprising the combination with a motor vehicle including a frame and steering column, of a pair of casings mounted at the 115 forward end of said frame, a reflector pivotally mounted in each casing, means for moving said reflectors including a pair of movable members, a manually controlled operating member mounted on said steering 120 column, means connecting said operating member with said movable members to equalize the tension in said members and means for limiting the throw of each of said movable members to limit the angular movement of said reflectors. 125

9. A device of the class described, comprising the combination of a casing; a reflector pivotally mounted therein; a single means for limiting the movement of said 130

reflector in both directions; said means being bodily adjustable; and means for moving said reflector.

10. A device of the class described, comprising the combination of a casing; a reflector pivotally mounted therein, means for moving said reflector, and a single stop for limiting the movement of said reflector in both directions, said stop being carried by said casing and bodily adjustable with reference thereto.

11. A device of the class described, comprising the combination of a casing; a reflector pivotally mounted therein; means for limiting the movement of said reflector in both directions, said means being bodily adjustable; and means for moving said reflector to the limit of its movement in both directions.

12. A device of the class described, comprising the combination of a casing; a reflector pivotally mounted therein; a sleeve extending through and adjustably mounted in said casing; a member extending through said sleeve and connected to the rear end of said reflector; means for moving said member; and means for limiting the movement of said member, carried by said sleeve.

13. A device of the class described, comprising the combination of a casing; a reflector pivotally mounted in said casing; a sleeve carried by and extending through said casing and adjustably mounted therein; a wire extending through said sleeve and connected to the rear end of said reflector; means carried by said sleeve for limiting the movement of said wire; means for moving said wire; and spring means for moving said reflector in one direction.

14. A device of the class described, comprising the combination of a casing; a reflector pivotally mounted therein; a tube carried by and extending through said casing; a sleeve adjustably mounted in said tube and provided with a transverse pin; a wire connected at one end to the rear end of said reflector and at the other end to an operating wire, said wire being provided with a loop of fixed dimensions through which said pin extends.

15. A device of the class described, comprising the combination of a casing; a re-

flector pivotally mounted therein; a sleeve extending through and adjustably mounted on said casing; a pin extending transversely of said sleeve; a wire extending through said sleeve and connected at one end to the rear end of said reflector and at the other end to an operating member, said wire being provided with a loop of fixed dimensions through which said pin extends; and a spring disposed to move said reflector in one direction.

16. A device of the class described, comprising the combination with a motor vehicle, of a pair of headlight casings carried thereby; a reflector pivotally mounted in each casing; means for moving said reflectors, including operating wires; a casing adapted to be secured to the steering column of the motor vehicle; an operating lever pivotally mounted in said casing; means for latching said lever in one position; connections between said lever and said operating wires; and spring means for moving said lever away from its latched position.

17. In a device of the class described, the combination of a casing, a reflector pivotally mounted therein, manually actuated means for moving said reflector to its limit of movement in one direction, automatic means for moving said reflector to its limit of movement in the opposite direction, and a single adjusting means for determining both the initial and terminal positions of said reflector.

18. In a device of the class described, the combination of plurality of head-light casings, a tiltable reflector in each of said casings, means to limit movement of each reflector independently of the other, means for moving said reflectors in unison to their individual limited positions.

19. In a device of the class described, the combination of a casing, a reflector tiltably mounted therein, stop means for the two limiting positions of said reflector, resilient means for holding said reflector in its normal limited position and means for resiliently holding said reflector in its other limited position.

In testimony whereof I affix my signature.

TRUMAN W. POST.
